(57) **CLAIM**

The ornamental design for an electrical power unit for a work surface, as shown and described.

DESCRIPTION

FIG. 1 is a top-front perspective view of an electrical power unit for a work surface showing our new design;

FIG. 2 a top-rear perspective view thereof;

FIG. 3 is a bottom-front perspective view thereof;

FIG. 4 is a bottom-rear view thereof;

FIG. 5 is a front elevation view thereof;

FIG. 6 is a rear elevation view thereof;

FIG. 7 is a top plan view thereof;

FIG. 8 is a bottom plan view thereof;

FIG. 9 is a right side elevation view thereof; and,

FIG. 10 is a left side elevation view thereof.

The broken lines are for the purpose of illustrating portions of the article that form no part of the claimed design.

1 Claim, 8 Drawing Sheets
